No. 37,119.

Patented September 6, 1904.

UNITED STATES PATENT OFFICE.

SIDNEY A. KELLER, OF NEW YORK, N. Y.

DESIGN FOR A BACK FOR HAND-MIRRORS OR SIMILAR ARTICLES.

SPECIFICATION forming part of Design No. 37,119, dated September 6, 1904.

Application filed August 9, 1904. Serial No. 220,125. Term of patent 3½ years.

To all whom it may concern:

Be it known that I, SIDNEY A. KELLER, a citizen of the United States, and a resident of New York, borough of Manhattan, in the county of New York and State of New York, have invented a certain new, original, and ornamental Design for the Back of a Hand-Mirror or Similar Article, of which the following is a specification.

10 The accompanying drawing is a view in elevation of the back of a hand-mirror having my design applied thereto.

What I claim is—

The ornamental design for the back of a hand-mirror or similar article, as shown.

SIDNEY A. KELLER.
